(57) **CLAIM**

I claim the ornamental design for a broom body, as shown and described.

DESCRIPTION

FIG. 1 is a perspective view of a first embodiment of a broom body according to the present invention.

FIG. 2 is a front elevational view of the broom body of FIG. 1.

FIG. 3 is a rear elevational view of the broom body of FIG. 1.

FIG. 4 is a first side elevational view of the broom body of FIG. 1.

FIG. 5 is a second side elevational view of the broom body of FIG. 1.

FIG. 6 is a top plan view of the broom body of FIG. 1.

FIG. 7 is a perspective view of a second embodiment of a broom body according to the present invention.

FIG. 8 is a front elevational view of the broom body of FIG. 7.

FIG. 9 is a rear elevational view of the broom body of FIG. 7.

FIG. 10 is a first side elevational view of the broom body of FIG. 7.

FIG. 11 is a second side elevational view of the broom body of FIG. 7.

FIG. 12 is a top plan view of the broom body of FIG. 7.

FIG. 13 is a perspective view of a third embodiment of a broom body according to the present invention.

FIG. 14 is a front elevational view of the broom body of FIG. 13.

FIG. 15 is a rear elevational view of the broom body of FIG. 13.

FIG. 16 is a first side elevational view of the broom body of FIG. 13.

FIG. 17 is a second side elevational view of the broom body of FIG. 13.

FIG. 18 is a top plan view of the broom body of FIG. 13.

FIG. 19 is a perspective view of a fourth embodiment of a broom body according to the present invention.

FIG. 20 is a front elevational view of the broom body of FIG. 19.

FIG. 21 is a rear elevational view of the broom body of FIG. 19.

FIG. 22 is a first side elevational view of the broom body of FIG. 19.

FIG. 23 is a second side elevational view of the broom body of FIG. 19; and,

FIG. 24 is a top plan view of the broom body of FIG. 19.

The broken lines shown in the drawings are for environmental purposes only and form no part of the claimed design.
